UNITED STATES PATENT OFFICE.

CARL JULIUS ÅBERG, OF STENSTORP, SWEDEN.

ROAD-MAKING.

1,327,131.

Specification of Letters Patent.

Patented Jan. 6, 1920.

Application filed September 26, 1916. Serial No. 122,282.

To all whom it may concern:

Be it known that I, CARL JULIUS ÅBERG, master builder, a subject of the King of Sweden, residing at Stenstorp, Sweden, have invented certain new and useful Improvements in Road-Making; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to road making and it has for its chief object to reduce the number of workmen necessary for producing a roadway made of macadam, crushed rock or the like. Another object is to provide a 20 method of road making in which the stones to be discharged on to the road bed are crushed on board a vehicle which is propelled during the crushing operation. Another object is to provide an improved road 25 making machine combining means for breaking stones and means for delivering the broken stones onto the road bed with means for spreading the broken stones in an even layer and means for compacting or 30 rolling the road bed before, or after, or both before and after the layer of stones has been spread thereon. A further object of my invention is generally to improve the structure and accelerate the operation of 35 road making machines.

In the accompanying drawings which illustrate by way of example various embodiments of my invention:

Figure 1 is a side elevation of my improved road making machine;

Fig. 2 is a plan thereof;

Fig. 3 is a detail section on the line A—B, Fig. 2;

Fig. 4 is a side elevation of a modified 45 form of road making machine;

Fig. 5 is a plan of the stone spreading device shown in Fig. 4;

Fig. 6 is a side elevation of another form of spreading device;

50 Fig. 7 is a plan thereof;

Fig. 8 is a sectional view of a third form of spreading device;

Fig. 9 is a plan thereof;

Fig. 10 is a sectional view of a fourth 55 form of spreading device;

Fig. 11 is a plan thereof;

Fig. 12 is a front elevation of an improved compacting roller.

Referring to Figs. 1 to 3, the tractor engine and the stone breaker are mounted on 60 separate frames designated by 1 and 2 respectively and connected with each other by means of a coupling pole comprising two parallel bars 3 having preferably a U-shaped cross-section as shown in Fig. 3, and rigidly 65 secured to each other at both ends. The coupling pole is pivotally connected with the frames 1 and 2 in the following manner: The front end of the coupling pole is suspended from a screw 4 provided at the top with a nut 5 which rests on a supporting lug 6 on the rear of the tractor frame; the lower end of the screw 4 is provided with an eye 7 loosely engaged by a horizontal pin 8 which connects the front end of the bars 3. At their 70 rear ends the bars 3 are rigidly connected together by means of a cross piece or lug 9 which is supported between two lugs 11 on the stone breaker frame and is loosely engaged by a vertical pin 10 secured to the 75 lugs 11.

In the space between the two parallel bars 3 are located two sprocket wheels 12 and 13 which are journaled in the bars 3 and form part of a driving connection for actuating the stone breaker shaft 15 from the power shaft 14 of the tractor. This driving connection further comprises sprockets 16 and 17 which are mounted on the shafts 14 and 15 respectively and connected 80 through suitable chains 18 and 19 with sprockets 20 and 21 which are universally jointed at 22 and 23 to the sprockets 12 and 13 respectively; (Fig. 2).

The stone spreading device or plow comprises two diverging plates or blades 24 forming a wedge which is pivotally mounted at its apex on a vertical shaft 25 journaled in lugs 26 projecting from the rear end of the frame 2. At its lower end the 100 shaft 25 is provided with two projections 28 and 29 which embrace the front ends of the plates 24. At its upper end the shaft 25 has a threaded portion which engages a similarly threaded bore in the lug 26 and 105 is provided with a handwheel 27 whereby the elevation of the front end of the plow over the ground can be varied as desired.

The rear end of the plow is carried by a pair of small wheels 30 whose axle 33 is 110 formed of two telescopic sections connecting together the rear ends of the blades 24,

The axle 33 is mounted in bearings 35 which may be raised or lowered by means of threaded rods 32 provided with hand wheels 27. Suitable runners may, if desired, be used instead of the carrying wheels 30. By operating the hand wheels 27 and 31 it is thus possible to vary the elevation of the plates 24 in order to obtain a uniform layer of stones of the desired thickness.

As shown in Figs. 1 and 2, the tractor is mounted on heavy rollers which compact the road bed before the broken stones are spread thereon. The stones are discharged from the stone breaker in front of the plow so that the stones which may be in excess at one place will be deflected along the plates 24 to some other point where the thickness of the string or layer discharged from the stone breaker is less. The rear end of the plow is preferably loaded with a weight in order to hold the wheels 30 firmly pressed against the ground.

At their lower ends the blades 24 are preferably provided with horizontal flanges 34 having a sharp front edge to enable the plow to cut its way through the mass of broken stones, whereby the spreading of such mass will be greatly facilitated.

Any suitable driving means may be used to drive the tractor and the stone breaker. I may, for example, drive the stone breaker by means of an electric motor receiving its current from a generator driven by an internal combustion engine on the tractor frame.

In Fig. 4 I have shown an embodiment of the invention which is more particularly intended for use in cases where a machine of large capacity is not required. The stone breaker is herein shown as being mounted on the tractor frame 40 so that the rollers 41 on which this frame is mounted will support the combined weight of the engine 43 and stone breaker 42. The engine is adapted to drive both the tractor and the stone breaker at the same time by means of suitable chains 45.

As in the first example the plow shown in Fig. 4 is adapted to be adjusted vertically with respect to the machine frame. The two diverging blades 44 of the plow are connected with each other, at an intermediate point of their length, by means of the front cross bar of a frame 47 in which are journaled a pair of rollers 57 which serve to compact the macadam spread in a uniform layer by the plow members 44. Two or more boxes 48 arranged on either sides of the rollers 57 may be filled with stones or other suitable weights when it is desired to increase the compacting action of the rollers 47. The plow members 44 may conveniently be provided with a joint at the point where they are connected with the frame 47 so that their ends may be moved toward or away

from each other as desired. When the machine is not working the jointed rear ends of the blades 44 may be moved close to the roller frame.

In Figs. 6 and 7 I have illustrated a device adapted to spread the macadam on the road while it is being discharged from the breaking device. This device consists of an inclined plate 49 which increases in width from its upper end toward its lower end and is so proportioned that the length of its lower transverse edge is substantially equal to the required width of the layer of macadam. The plate 49 is provided with upstanding side walls 39 and a number of diverging longitudinal partitions 50 whereby the macadam fed at the narrow upper end of the inclined plate will be evenly distributed over the whole width of the lower end of the road bed.

In Figs. 8 and 9 I have shown a spreading device comprising two co-axial hollow drums 51 arranged symmetrically with respect to the discharge opening of the stone breaker. The drums 51 are each provided internally with a screw shaped partition and with peripheral apertures 52 the size of which may be regulated by means of suitable shutters. The drums may be rotated from the driving mechanism of the breaker by means of suitable connections such as gears, a chain or a belt. It will be readily understood that as the broken stones are fed to the inner ends of the hollow drums 51, they will be moved outwardly and will fall out through the successive apertures 52 so that they will be spread evenly on the road. The breaker and spreading device may, if desired, be placed at the front end of the machine frame.

With the construction shown in Figs. 1 to 3 the machine rolls the road bed immediately before the macadam is spread thereon. With the construction shown in Figs. 4 to 9 the machine compacts the road bed before as well as immediately after the spreading of the macadam. I shall now describe with reference to Figs. 10 and 11 a form of spreading device which is adapted to be secured to the front part of the machine frame so that the rollers carrying the machine will act on the road bed only after the macadam has been spread thereon. This spreading device which combines elements of the device in Figs. 4 and 5 and Figs. 6 and 7 respectively, consists of an inclined plate 59 and a snow-plow-shaped member 60 below said plate. The plate 59 is tapered to conform to the shape of the member 60 and it is curved downwardly on three sides from a point (shown by a dotted circle in Fig. 10) where the macadam is fed from the stone breaking device. Radial partitions 58 are provided to distribute the macadam in an even layer. The spreading device is mounted on the front edge of the machine frame which

moves in the direction of the arrow (Fig. 10) so that the macadam which tumbles down along the front and side portions of the plate 59, will be engaged by the plow-shaped member 60 which will spread the material in an even layer upon the road.

Fig. 12 shows a preferred form of roller which may be adopted for the rollers for compacting the road bed before as well as 10 after the spreading of the macadam. As shown these rollers or sets of rollers have a curved generatrix which conforms to the profile of the road.

While the invention has been described 15 with particular reference to certain details of construction, the same is not to be considered as limited thereto, as many changes can be made and still fall within the scope of the invention set forth in the following 20 claims.

I claim as my invention:

1. A road making machine comprising a vehicle, means for propelling said vehicle, and means operatively connected with said propelling means for breaking stones and causing the broken stones to be discharged onto the road bed at a speed proportional to the rate of travel of the vehicle, both said means being carried by said vehicle.
2. A road making machine comprising a vehicle, a stone breaker on said vehicle, means for simultaneously propelling said vehicle and actuating said stone breaker at a speed proportional to the rate of travel 35 of said vehicle, means for directly discharging the broken stones from the stone breaker onto the road bed, and means for rolling the discharging stones as the vehicle is being propelled.
3. A road making machine comprising a vehicle having a frame and a driving axle, a source of power and a stone breaker on said frame, connections between said source of power, stone breaker and driving axle 45 for simultaneously operating said stone breaker and rotating said driving axle, means for discharging the broken stones onto the road bed, and means for rolling the discharged stones as the vehicle is being propelled.
4. A road making machine comprising a vehicle having a frame and a driving axle, a source of power and a stone breaker rigidly mounted on said frame, connections 55 between said source of power, stone breaker and driving axle for simultaneously operating said stone breaker and rotating said driving axle, means for discharging the stones from said stone breaker onto the road

bed as a freely running stream, and means 60 for laterally spreading said stream without interrupting the same.

5. A road making machine comprising a vehicle having a frame and a driving axle, a source of power and a stone breaker rigidly mounted on said frame, connections between said source of power, stone breaker and driving axle for simultaneously operating said stone breaker and rotating said driving axle, means for discharging the 70 stones from said stone breaker onto the road bed as a freely running stream, means for laterally spreading said stream without interrupting the same, and means for rolling the discharged stones over the whole width 75 of the layer formed.

6. A road making machine comprising a vehicle having a frame and a driving axle, a source of power and a stone breaker rigidly mounted on said frame, connections 80 between said source of power, stone breaker and driving axle whereby the latter two may be operated simultaneously by said source of power, means for discharging the broken stones onto the roadbed and means for 85 spreading said stones in a lateral direction while they are being discharged, said spreading means comprising an inclined surface sloping forwardly and laterally from a point at the front of the vehicle and 90 a plow shaped member at the lower edge of said surface.

7. A road making machine comprising a vehicle having a frame, a driving axle and compacting rollers, a source of power and a 95 stone breaker rigidly mounted on said frame, connections between said source of power, stone breaker and driving axle whereby the latter two may be operated simultaneously by said source of power, 100 means for discharging the broken stones onto the roadbed in front of said rollers, and a spreading member inserted in the path of the stones being discharged, said spreading member comprising a forwardly and 105 laterally sloping shell projecting from the front of the vehicle, radially disposed partitions on said shell for guiding the falling stones, and a plow shaped member at the lower edge thereof.

In testimony that I claim the foregoing as my invention, I have signed my name in presence of two subscribing witnesses.

CARL JULIUS ÅBERG.
